UNITED STATES PATENT OFFICE.

RICHARD MONTGOMERY, OF NEW YORK, N. Y.

IMPROVEMENT IN IRON CARS.

Specification forming part of Letters Patent No. 29,510, dated August 7, 1860.

To all whom it may concern:

Be it known that I, RICHARD MONTGOMERY, of the city, county, and State of New York, have invented certain new and useful Improvements in Iron Cars; and I do hereby declare that the following is a full, clear, and exact description thereof, reference being had to the accompanying drawings, forming a part of this specification, and in which—

Figure 1 represents a side view of the frame of the car, a part of the covering being removed. Fig. 2 represents a section on line A B, Fig. 1, and A C, Fig. 3. Fig. 3 represents a section on line A D, Fig. 2, or a longitudinal section through the center of the car, the line being vertical. Figs. 4, 5, and 6 represent on an enlarged scale detached sections of parts of the car to show more fully the mode of uniting the different parts. Figs. 7 and 8 represent the coupling-pieces by which the top, bottom, and cross pieces are united.

The frame of the car is composed of longitudinal side and base pieces A, arched top pieces B, and cross floor-pieces C. These pieces are all of corrugated iron or other metal, and correspond with each other in the form of the corrugation—that is to say, each has the same form when cut through on a line at right angles to the line of the corrugation.

The base-pieces A have margins a a, and the top pieces B have margins b b, while the cross or floor pieces C have margins c c. The margins a a of the base-pieces A afford a ready means whereby the frame can be securely fastened to the truck-frame of the car, and the margins b b of the arched top pieces B furnish an even surface, to which the corrugated iron covering F is fastened by rivets, while the margins c c of the cross-pieces C afford the necessary support for the arched and corrugated floor-supports D. The floor E, which is composed of wood cut into boards of the proper length, width, and thickness, rests on the cross-pieces C and also on the center of the arched corrugated iron supports D.

If desired, wooden pieces e may be inserted into the upper corrugation in the cross-pieces C for the purpose of receiving screws or nails by which to hold or fasten down the flooring E.

The mode of fastening the curved top pieces B to the cross-pieces C and side or base

pieces A is fully shown in Figs. 4 and 5, and is effected in a simple yet firm and durable manner as follows: The coupling-piece H is first placed with its lower projection H' in the upper corrugation in the base-piece A. The top piece B is then cut out at its end so as to fit over the upper projections H' H', as shown in Figs. 5 and 6. The cross-piece C is then placed over the projections H' H' and abutting against the end of the top piece B, (see Fig. 4,) which is a section on lines a b, Figs. 5 and 6. The other coupling-piece G is now placed in position, as shown in Figs. 2 and 5. It will thus be seen that the projection G' of the coupling-piece G fits into the central corrugation in the pieces B and C, and also in between the projections H' H' of the coupling-piece H, while its outer sides fit over the outer corrugations in the pieces B and C and thus hold the parts securely in place. To hold the parts still more firm bolts or rivets h may be passed through the coupling-pieces and the ends of the pieces A, B, and C, as fully shown in the drawings.

The lower part of the car may be covered with smooth sheets; but I prefer to make the top of corrugated sheets, since it adds very much to the strength of the car and also gives it a more finished appearance. The number of the curved corrugated top pieces B may be varied to suit the purposes to which the car is to be used. When great strain and weight is to be borne, then their number will necessarily be greater than when the car is to be used on roads where but little business is done. The sheets which compose the covering may be united at their ends, as shown at f, Fig. 1, and at their sides, as shown at g, Fig. 2. The ends of the plates should meet over one of the pieces B, so that their ends can be securely fastened or riveted down. The coupling-pieces H and G may be of cast metal.

The object of my invention has been to produce an iron car which could be built cheap, while at the same time it should possess the necessary strength and lightness to recommend it to favor.

In constructing a car after my plan the iron can be rolled out and corrugated with great rapidity, and consequently can be afforded at a very low rate, while the arrangement of

the corrugations renders the car very strong and easily united.

Of the advantages in the use of an iron car there is no necessity to speak, since it has long been proved that if an iron car could only be built which should combine cheapness and lightness, while at the same time possessing great strength and simplicity of construction, it would be a great addition to the facilities of safe and quick traveling by railroads.

Having described my improved iron car,

what I claim as my invention, and desire to secure by Letters Patent, is—

The combination of the curved corrugated top pieces B with the corrugated side or base pieces A and coupling-pieces H and G, the whole arranged in relation to each other as and for the purposes set forth.

RICHARD MONTGOMERY.
